LOOSE LEAF BINDER

Arthur W. McClure, Syracuse, N. Y., assignor to
McMillan Book Company, Syracuse, N. Y., a
corporation of New York

Application April 19, 1934, Serial No. 721,319

3 Claims. (Cl. 129—8)

This invention relates to improvements for loose leaf binders in which an extensible back member is provided with reversely arranged leaf impaling members or posts.

5 An object of the invention is to provide a loose leaf binder comprising two back or cover sections which are movable relative to each other, to vary the leaf carrying capacity of the binder.

Another object of the invention is to provide 10 a loose leaf binder of the above mentioned class with simple and efficacious means for releasably limiting the separating movement of the binder sections, whereby said sections may be moved to a maximum extended position beyond the full leaf 15 confining position where the leaves may be removed from the leaf impaling members or placed thereon.

A further object resides in providing the binder sections with hinge means effective when the sections are in the maximum extended position to permit said sections to be moved into angular relation whereby the removal of the leaves from or the placement of the leaves in the binder is facilitated.

25 Other objects and advantages pertaining to the specific parts of the device will be brought out in the following description taken in connection with the accompanying drawings, in which:

Figure 1 is a top plan view of a loose leaf binder embodying the various features of this invention, the outer portions of the covers being broken away and the sections of the binder being shown in the contracted position.

Figure 2 is a plan view of the binder similar to that shown in Figure 1 and illustrating the binder sections by full lines in the partially extended position adapted to receive its full capacity of leaves, one of the sections being illustrated by broken lines in the position assumed when fully extended.

Figure 3 is an enlarged transverse sectional view taken on line 3—3, Figure 2, illustrating the binder sections in the fully extended position by full lines, and in angular relation in the fully opened position by broken lines.

Figure 4 is a detail horizontal sectional view taken on line 4—4, Figure 3.

Figure 5 is an enlarged transverse sectional view taken on line 5—5, Figure 1.

Figure 6 is an enlarged detail longitudinal sectional view taken on line 6—6, Figure 1.

Figure 7 is a detail horizontal sectional view taken on line 7—7, Figure 6.

Figure 8 is a perspective view of an end portion

of the binder illustrating the same in the fully opened position.

Figure 9 is a detail sectional view taken on line 9—9, Figure 8.

The binder as illustrated in the drawings comprises covers 1 and 2, formed in any suitable manner and which are hingedly connected as at 3 and 4 to a respective back section 5 and 6 preferably constructed of sheet metal.

These back sections 5 and 6 are L shape in cross section and are arranged with the wider legs as 5' and 6' normally positioned one over the other in juxtaposed relation, while the shorter legs as 5'' and 6'' of the sections are arranged at the outer edges of the corresponding wider legs adjacent the respective covers 1 or 2 and to extend inwardly therefrom. Each leg 5'' and 6'' has the outer longitudinal edge thereof return bent as at 8 to reinforce the same. To each leg member 5' and 6' are fixedly secured a plurality of, in this instance, two, relatively long leaf-impaling members or posts 10, positioned one near a respective end thereof, and a relatively short leaf-impaling member or post 11 positioned intermediate the end posts 10 substantially midway between the ends of the corresponding back section. The intermediate posts 11 are obviously in line with each other and are of such a length that when the back sections 5 and 6 are in their innermost or fully contracted position, the inner ends thereof will terminate in slightly spaced relation, as illustrated in Figure 5. The posts 10 positioned at either end of the back sections are arranged in offset relation and are of such a length that when the sections are in the innermost or fully contracted position, they will extend from the leg to which they are attached to within a relatively short distance of the opposite leg as illustrated in Figure 1, it being understood that the posts 10 and 11 are spaced longitudinally of the sections so as to readily receive suitably perforated leaves thereon in the conventional manner.

At each end of the back section 5 is provided an upstanding guide or hinge member 14 having a side and end provided with inwardly extending laterally disposed flanges 15, which are secured by spot welding, rivets, or the like, to the adjacent portions of the legs 5' and 5'' of the section. These guide members 14 are of substantially the same length as the wider leg 5' of the section and each is provided with a slot 16, which extends longitudinally therethrough with the ends of the slot terminating a relatively short distance from the corresponding ends of the

guide member. The upper longitudinal edge of the guide member 14 has a portion thereof return bent to form a guide channel 18 at the inner face of said member.

5 The other back section as 6 is also provided at either end thereof with a guide or hinge member 19, normally positioned adjacent the inner face of the corresponding guide member 14 with the upper longitudinal edge thereof registering 10 in the respective guide channel 18. These guide members 19 are also provided with inwardly extended lateral flanges as 20 which are secured as by rivets, spot welding, or the like, to the adjacent portions of the back section 6. The inner or free 15 end of each guide member 19 has secured thereto a shouldered pin 22, which travels in the adjacent slot 16 provided in the other guide member 14.

It will now be observed that the guide members 14 and 19 and, therefore, the back sections 5 and 20 6, are slidably and pivotally secured together by the slot and pin connection, so that when the sections are fully extended with the pins 22 positioned at the outer end of the slots 16, the sections 25 may be rocked relative to each other about the pins as a pivot, until the sections assume a more or less tilting or angular position relative to each other as clearly illustrated in Figure 8 and by broken lines in Figure 3.

In order that this tilting action of the sections 30 30 may be freely permitted, one of the sections as 6 has the wider leg 6' thereof somewhat shorter in width than the corresponding leg of the other section, so that when the sections are fully extended, the adjacent edges of the legs 5' and 6' 35 will be spaced apart sufficiently to permit said edges to pass without coming into contact with each other.

Further, the guide members 19 on the inner section 6 may, as shown in Figures 3 and 8, be provided with recesses or notches 24, in the bottom edge thereof adapted to receive the adjacent portion of the inner longitudinal edge of the leg 5' of the other section. These recesses or notches 40 24 are not only of such a depth as to permit an additional pivotal movement of the sections, but the inner ends thereof form stops engaging the legs 5' for limiting the tilting movement of the sections and preventing the longitudinal edge of the leg 6' coming into contact with the leg 5' 45 and becoming bent or damaged thereby. The leg 5' of the section 5 may, as shown in Figures 8 and 9, be provided with a metal abutting clip 25 at either end thereof adapted to engage the guide member 19. These abutting clips may extend 50 over the material 26 such as leather, cloth, or the like, which is usually applied to the outer surface of the sections 5 and 6 to protect such material as the leg 5' moves into engagement with the guide member 19. This tilting of the back sections 5 55 and 6 to the open position shown in Figure 8 and also by broken lines in Figure 3 is for the purpose of moving the posts 10 connected therewith out of parallel planes into planes extending substantially at right angles to each other, with the ends 60 of the posts of each section sufficiently spaced from the corresponding post of the other section to permit the leaves to be readily removed from the said posts or placed thereon.

The moving of the back sections 5 and 6 relative to each other is also utilized to enable the binder to be readily adjusted to a greater or less width, whereby the leaf carrying capacity of the binder may be increased. In order that the extension of the sections may be limited at an intermediate position thereof, where the binder is

adapted to carry a maximum number of leaves, I have provided a releasable stop mechanism which in this instance comprises an inwardly extending lug 28 formed in this instance by pressing up a portion of the leg 5' of the outer positioned 5 section 5.

This stop lug 28 is formed in close proximity to the inner edge of the leg 5' substantially midway between the ends thereof. The lug extends inwardly through an elongated slot 29 which extends inwardly from the outer or free longitudinal edge of the leg 6' of the inner positioned section 6.

A latch 30 is pivotally mounted intermediate its ends as at 31 to the leg 6' of the inner section adjacent the slot 29, so that the holding end 10 of the latch will extend across the slot 29 in the path of movement of the stop lug 28 for engaging said lug and preventing further outward relative movement of the back sections. The latch 30 may be manually moved out of the path of 15 movement of the lug 28 through the medium of a slide bar 32 and link 33. The slide bar 32, in this instance, is positioned adjacent the inner face of the leg 6'' of the section 6, and is slidably secured to said leg by a pair of pin and slot connections 25 illustrated at 34, Figures 4 and 6.

The outer end of the slide bar 32 extends outwardly through a slot provided between the inner end of the guide 19—and leg 6'' beyond said guide member and is bent laterally to form a finger 30 piece 32', by which the slide may be readily moved longitudinally. The inner end of the slide bar 32 is provided with a recess 34' at the inner longitudinal edge thereof adapted to receive one end of the link 33 therein. The other end of the link 33 is pivotally connected as at 35 to the inner end of the latch 30, while the end of the link 33 adjacent the slide bar 32 is slidably connected to the leg 6' by a pin and slot connection 36, see Figure 6. In order that the latch 30 may 40 be automatically restored to its operative position in the path of movement of the lug 28, as the back sections are moved inwardly toward each other, from the fully extended position, the inner end of the latch adjacent the pivot 35 is 45 formed with a cam surface 30' adapted when the opposite end of the latch is moved out of the operative position in the path of movement of the lug 28, to move across the slot 29 in the path of movement of said lug so as to be engaged thereby 50 as said lug moves inwardly and thus cause the latch to be rocked about the pivot 31 to the operative position.

It will now be observed that the relation of the lug 28 and latch 30 are such that when the back 55 sections are maintained thereby in the parallel extended position where the binder is adapted to carry the maximum number of leaves, the leg members 5' and 6' of said sections will be maintained with their inner longitudinal edges in 60 overlapping relation, so that, although the back sections are moved outwardly relative to each other, there will be no space appearing, from the outside, between the back sections, and that the binder will present substantially the same general appearance from the outside as when the sections are in their innermost contracted position.

It will also be readily understood that when it 70 is desired to add leaves to the binder or to remove leaves therefrom, it is only necessary for the operator to press lightly on the finger piece 32' to effect the inner longitudinal movement of the slide bar 32, whereupon the latch 30 will release the stop lug 28 as illustrated by broken 75

lines, Figure 2, and permit the sections to be moved outwardly to the fully extended position and thence angularly about the pins 22 as a pivot to the full open position. When it is again desired to close the binder, it is only necessary to rock the sections 5 and 6 about the pins 22 to again bring them into co-operative alinement, after which the sections may be readily moved inwardly toward each other to the fully collapsed or leaf retaining position.

10 Although I have shown and particularly described the preferred embodiment of my invention, I do not wish to be limited to the exact construction shown, as various changes in the form and relation of the parts thereof may readily be made without departing from the spirit of this invention as set forth in the appended claims.

I claim:

1. In a loose leaf binder, an extensible back comprising a pair of superposed back sections, guide plates connected with the back sections and slidably mounted adjacent each other, means connecting said guide plates comprising a slot in one of the said plates, and a pin secured to the other plate and movable in said slot whereby the back sections may be moved outwardly from a collapsed position in superposed relation to an extended position in transversely spaced relation, one of said plates being provided with a recess adapted to receive therein the adjacent portion of the back section secured to the other plate, whereby said back sections may swing about the pin as a pivot into angular relation.

2. In a loose leaf binder, an extensible back member comprising a pair of superposed back sections mounted for movement relative to each other, coacting leaf-impaling elements associated

with the back sections and adapted to secure leaves in the binder during the extension of said sections within certain limits, releasable cooperating means associated with the back sections adapted to limit the relative movement thereof, hinge means connecting the back sections and effective when said back sections are in fully extended position to permit said back sections and the elements connected therewith to swing into angular position, and one back section having 10 slots therein adapted to cooperate with the other of said back sections for limiting the angular movement of the back sections relative to each other.

3. A loose leaf binder comprising a pair of 15 superposed back sections mounted for movement relative to each other and adapted to have various positions relative to each other, a closed position, an extended position, and a position substantially at right angles to each other, said 20 binder being constructed and arranged so as to enable said back sections to be manually moved into said relationships, a latch operatively connected with one back section and a latch-engaging member operatively connected to the other 25 back section, said latch and latch engaging member being in operative engagement in said extended position and being movable out of engagement to enable the back sections to be moved to the angular relationship, said latch having 30 cam means associated therewith engageable with the latch engaging member for moving the latch back into position to engage said latch-engaging member when the back sections are moved from the angular relationship to the closed position. 35

ARTHUR W. McCLURE.
